US0D1030646S

(12) **United States Design Patent** (10) **Patent No.:** **US D1,030,646 S**
(45) **Date of Patent:** **** Jun. 11, 2024**

(54) **CHARGER**

(71) Applicant: **Guangdong Aoyun Technology Co., Ltd.**, Huizhou (CN)

(72) Inventor: **Xueping Zhu**, Rucheng (CN)

(73) Assignee: **Guangdong Aoyun Technology Co., Ltd.**

(**) Term: **15 Years**

(21) Appl. No.: **29/839,535**

(22) Filed: **May 23, 2022**

(51) LOC (14) Cl. **13-02**

(52) U.S. Cl.

USPC **D13/107**

(58) **Field of Classification Search**

USPC D13/103, 107, 108, 110, 118, 119, 156,

D13/184, 199

(57) **CLAIM**

The ornamental design for a charger, as shown and described.

DESCRIPTION

FIG. 1 is a first perspective view of a charger showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the charger thereof.

The broken lines shown in the drawings depict portions of the charger that form no part of the claimed design.

1 Claim, 9 Drawing Sheets
